UNITED STATES PATENT OFFICE

164,301

PLASTIC FILM MATERIAL

Louis J. Harmon, Peabody, Mass.

Application July 20, 1949, Serial No. 4,030

Term of patent 3½ years

(Cl. D92—1)

To all whom it may concern:

Be it known that I, Louis J. Harmon, a citizen of the United States, residing at Peabody, State of Massachusetts, have invented a new, original, and ornamental Design for a Plastic Film Material, of which the following is a specification, reference being had to the accompanying drawing, forming a part hereof in which the figure shows a plan view of the plastic film material. The opposite side is plain.

The design unit is outlined by broken lines and is repeated over the material as indicated by the extensions beyond the unit boundaries.

I claim:

The ornamental design for a plastic film material, as shown and described.

LOUIS J. HARMON.
